UNITED STATES PATENT OFFICE.

HERBERT TAUTZ AND FRANK E. DION, OF MILWAUKEE, WISCONSIN, ASSIGNORS TO AMERICAN GRINDER MANUFACTURING COMPANY, OF MILWAUKEE, WISCONSIN, A CORPORATION OF WISCONSIN.

TOOL GRIP.

Application filed May 15, 1922. Serial No. 561,030.

To all whom it may concern:

Be it known that we, HERBERT TAUTZ, a citizen of the German Republic, and FRANK E. DION, a citizen of the United States, and residents of Milwaukee, in the county of Milwaukee and State of Wisconsin, have invented new and useful Improvements in Tool Grips, of which the following is a description, reference being had to the accompanying drawings, which are a part of this specification.

The invention relates to hand grips for tools.

The general object of the invention is to provide a sheet metal hand grip of inexpensive construction that may be readily applied to the tool even after such tool has been given its final form.

A further object of the invention is to provide a grip that may be used as a center grip or as an end grip when an end cap is secured to it.

A further object of the invention is to provide a grip in which the limiting stops for the grip are enclosed by it, thus preventing any possibility of bruising or lacerating the hands of the user.

With the above and other objects in view the invention consists in the construction and the several features of construction hereinafter described and claimed and all equivalents.

In the drawings: Fig. 1 is an elevation view of a tool equipped with hand grips embodying the invention; Fig. 2 is a vertical sectional view through the center hand grip; Fig. 3 is a vertical sectional view through the end hand grip.

In the drawings we have shown, for the purpose of illustrating the invention, a socket wrench 4 having a handle 5 of the bit brace type provided with a center grip and an end grip embodying the invention.

In each instance the hand grip embodying the invention consists of a tubular member 6 of sheet metal having reduced tubular end

portions 7 rotatably mounted on the handle 5 and an annular groove 8 adjacent at least one end of said member though grooves adjacent both ends are provided. Each tubular member 6 is formed from a sheet metal blank that is given a preliminary shaping and is then placed around the handle and given its final shape by the use of suitable dies. No welding of the adjoining edges 9 of the member or the use of retainer bands is necessary.

The handle 5 of the tool is provided with usual stop projections 10, but contrary to the usual practice these projections are enclosed within the grip adjacent the tubular end portions 7 so that any chance of injury from contact with such projections is eliminated. This is made possible by the formation of the grip around the tool.

When used as an end grip, a pressed metal cap 11 is fitted over the outer end of the tubular member and preferably has its edge 12 crimped within the adjacent groove 8, said end cap being in end thrust engagement 70 with the end of the tool handle.

By constructing the grip of pressed sheet metal the tool itself may be bent to shape and heat-treated or otherwise processed or worked before applying the grip or grips 75 embodying the invention.

What we claim as our invention is:

The combination, with a tool handle, of a pressed metal tubular one-piece hand-grip rotatably mounted on the handle and provided with reduced tubular end portions and an annular groove adjacent one end, a cap in end thrust engagement with said handle and having an annular edge extending into said groove, and spaced stop projections on 80 the handle and disposed within the grip adjacent said end portions for positioning said grip on the handle.

In testimony whereof, we affix our signatures.

HERBERT TAUTZ.
FRANK E. DION.
